US00D763850S

(12) **United States Design Patent**
Aumiller et al.

(10) **Patent No.:** US D763,850 S
(45) **Date of Patent:** ** Aug. 16, 2016

(54) **ELECTRONIC DEVICE**

(71) Applicant: **SAMSUNG ELECTRONICS CO., LTD.**, Suwon-si (KR)

(72) Inventors: **Curtis Aumiller**, San Jose, CA (US); **Pranav Mistry**, Cupertino, CA (US); **Chengyuan Wei**, Dalian (CN)

(73) Assignee: **SAMSUNG ELECTRONICS CO., LTD.**, Suwon-si (KR)

(**) Term: **14 Years**

(21) Appl. No.: **29/453,910**

(22) Filed: **May 3, 2013**

Related U.S. Application Data

(63) Continuation of application No. 29/449,802, filed on Mar. 15, 2013, now Pat. No. Des. 709,875.

(57) **CLAIM**

The ornamental design for an electronic device, as shown and described.

DESCRIPTION

FIG. 1 is a top front perspective view of an electronic device showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an additional top front perspective view thereof with the electronic device shown at a different direction from that of FIG. 1; and,

FIG. 9 is an additional top front perspective view thereof with the electronic device shown in an alternate position and with the terminal portion of the band partially truncated.

The broken lines shown in the drawings represent portions of the electronic device that form no part of the claimed design.

1 Claim, 4 Drawing Sheets
